PROPELLER

William J. H. Engelke, Fort Worth, Tex.

Application December 10, 1947, Serial No. 143,083

Term of patent 14 years

(Cl. D34—15)

To all whom it may concern:

Be it known that I, William J. H. Engelke, a citizen of the United States of America, residing at Fort Worth, in the county of Tarrant and State of Texas, have invented a new, original, and ornamental Design for a Propeller, of which the following is a specification, reference being had to the accompanying drawing, forming part thereof.

Figure 1 is a perspective view of a propeller showing my new design.

Figure 2 is a side elevational view thereof.

Figure 3 is a plan view of a propeller showing my new design, and

Figure 4 illustrates a front elevational view thereof.

I claim:

The ornamental design for a propeller, substantially as shown.

WILLIAM J. H. ENGELKE.
